UNITED STATES PATENT OFFICE.

JONAS NORTHRUP, OF HOPEDALE, MASSACHUSETTS, ASSIGNOR TO DRAPER COMPANY,
OF HOPEDALE, MASSACHUSETTS, A CORPORATION OF MAINE.

CLOTH-BEAM.

1,082,166.

Specification of Letters Patent. Patented Dec. 23, 1913.

Application filed September 19, 1911. Serial No. 650,208.

To all whom it may concern:

Be it known that I, JONAS NORTHRUP, a citizen of the United States, residing at Hopedale, in the county of Worcester and State of Massachusetts, have invented an Improvement in Cloth-Beams, of which the following description, in connection with the accompanying drawings, is a specification, like letters on the drawings representing like parts.

This invention relates to looms, and more particularly to the cloth beam upon which the cloth is wound as it is woven.

It is desirable that the end of the cloth first woven be conveniently connected to the cloth beam so that as the latter is rotated during the operation of the loom it will wind the cloth thereon. When a desirable length of cloth has been woven and wound on the cloth beam it is desirable that the beam be removed from the roll of cloth without the necessity of unwinding the cloth therefrom and without materially disturbing the convolutions of the cloth roll.

With these and other objects in view the aims and purposes of the present invention are primarily to provide means, whereby the end of the cloth may be conveniently attached to the cloth beam, and the cloth wound thereon, and whereby also when the desired amount of cloth has been woven and wound on the beam, the cloth roll may be readily and conveniently removed from the beam without disturbing the convolutions thereof, all of which will best be made clear from the following description and accompanying drawings of one form of means for carrying the invention into practical effect, it being understood that details may vary within the true scope of the invention, which is definitely set forth by the claims.

In the drawings: Figure 1 is a front view of a cloth beam and its associated parts containing the essentials of the present invention, said beam being indicated as in operative or cloth winding position in the loom; Fig. 2 is a section on line 2—2, Fig. 1; Fig. 3 is a section on line 3—3, Fig. 2; Fig. 4 is a section on line 4—4, Fig. 2; Fig. 5 is a section on line 5—5, Fig. 1; and Fig. 6 is a view of the cloth beam detached from the loom.

The loom frame may be of any usual or desired form and character, and since the

present invention is directed to the cloth beam and its associated parts, only so much of the loom frame and the weaving mechanism is shown, as seem necessary to make clear the present invention and its relation thereto.

The stands 1 at either side of the loom frame are provided with brackets or other like supports 2, 3, for sustaining the cloth beam and its holding and operating means. Rotatably mounted in a suitable bearing 4 supported by the bracket 2, is a shaft or rotatable member 5, Fig. 1, having fixed thereto the friction wheel 6, Fig. 5, about the periphery of which passes the friction straps 7 and 8, one end of each being secured to an arm 9 projecting from the hub of a sprocket wheel 10 loosely mounted on the shaft 5. As one means for connecting the friction bands 7 and 8 to the arm 9 of the sprocket wheel, said arm 9 may be provided with pins 11 and 12 about which the hooked ends 13 and 14 of the said straps may engage, substantially as indicated by Fig. 5. The other ends 15 and 16 of the friction bands 7 and 8 are turned outward and are connected by a clamping device, which, in the form of the invention illustrated, comprises a screw bolt 17 passed through the ends 15 and 16 of the straps and having a nut 18 on one end portion and a cam lever 19 pivoted at 20 to the other end, the construction being such that by swinging the lever 19 into the position shown, the ends of the straps 7 and 8 may be drawn toward each other and said straps be caused to bind upon the friction wheel 6. By adjusting the nut 18 the degree of frictional resistance to relative movement between the straps and friction bands may be varied to suit conditions of use. The sprocket wheel 10 may be driven from any suitable power as by the sprocket chain 21, which, if desired, may be connected with the usual sand roll, not shown, but well understood by those skilled in the art. If desired also the friction straps 7 and 8 may be lined with suitable friction material 22, such as leather or the like.

From the construction described it will be apparent that the shaft 5 is driven from the sprocket chain 21 through the medium of a friction device, to the end that while the sprocket chain and sprocket wheel may be uniformly driven at uniform speed, the

shaft 5 and perforce the cloth beam, as will later appear, may be driven at varying speed as the cloth roll on the beam increases in diameter.

5 Mounted on the shaft 5 is a beam holder and driver 23, Figs. 2, 3 and 4, preferably formed in general disk shape and having a projecting portion 24 extending from its face adapted to engage the inner end portions of the independent beam sections 25 and 26 and maintain said sections from collapsing, as will more fully appear. The projecting portion 24 may, if desired, be formed as a ring extending from the inner face of the holder 23.

10 Mounted in a suitable bearing 28 in the bracket 3, Fig. 1, is a stem 27 having a beam holder 29 similar to the beam holder 23, as so far described, and disposed between the 20 bracket 3 and the outer face of the beam holder 29 is a spring 30 acting normally to maintain the holder 29 pressed toward the holder 23 in axial alinement therewith, a pin 31 or other stop serving to limit the 25 movement of the holder 29, as will be clear from Fig. 1.

15 As hereinbefore noted the cloth beam comprises a plurality of independent sections, two being indicated in the present form of 30 the invention, and said sections are complementary, so that when assembled in operative relation they will produce a cloth beam having a substantially cylindrical or other shaped surface on which the cloth may be 35 wound.

20 From the construction thus far described, it will be apparent that if the independent sections which together form the cloth beam, have their ends seated against the inner 40 faces of the beam holders 23 and 29, that the spring 30, or other medium employed to force the holders against the ends of the sections, will cause the holders to maintain the independent sections of the beam in assembled relation. As the cloth is then 45 wound on the beam by the action of friction driving means described, or other device, the convolutions of the cloth will maintain the sections from separating radially, while the 50 projections or rings 24 will prevent the sections from collapsing. When, however, the beam and its load are taken from the loom, which may be done readily by slightly separating the beam holders, the beam holders 55 no longer prevent collapse of the beam sections, so that they may be readily withdrawn from the clutch roll.

25 While the described construction presents a good practical form of the present invention, the latter also contemplates means on the holders themselves for preventing radial separation of the beam sections from each other and devices also for forcing adjacent edges of two sections together in order to 60 hold the end of the cloth between them. To

the above ends the holder 29 is provided with the projections 32 which, if desired, may be arranged in separate relation about the periphery of the holder 29, substantially as indicated in Fig. 1, said projections being 70 adapted to engage the exterior surface of the edge portions of the sections 25 and 26 and maintain said sections from separating radially. The holder 23, at the opposite end of the cloth beam when in operating position is provided with a projection 34 for engaging the exterior of one section of the beam, as 26, and a projection 35 for engaging the exterior of the other section of the beam, said latter projection 35, being preferably provided with a curved surface, as 80 shown, so that the parts may be more conveniently assembled. In assembling the parts and placing the beam in operative position in the loom, one of the sections, as 26, is first placed between the holders 23 and 29, and then one end of the other section is placed against the holder 29 and its other end pressed downward over the curved surface of the projection 35, whereupon, when the end of the section passes below the lip of the projection, the parts snap into locking position as will be readily understood. In order that the section previously put in place may not drop from between the holders 85 when the other section is being put in position, the projection 34 of the holder 23 is made somewhat longer, as indicated in Figs. 1 and 3, than the projection 35, the construction being such that while the section 90 last to be put into position causes separation of the holders 23 and 29, such separation is not sufficient to cause the section already in position to be released.

95 In order that the independent sections 105 form the cloth beam may clamp the edge of the cloth between them, each of the sections 23 and 29 is provided with a section expander 110 36 which projects radially outward from the ring 24, substantially as indicated in Fig. 2. This section expander on the holders 115 23 and 29 is adapted to engage between the longitudinal edges of the two independent sections 25 and 26 and to force their opposite adjacent edge portions 37 and 38 together upon the cloth 39, as indicated in Fig. 2. If desired, the section expanders 120 36 may have their edges 40 inclined somewhat, as indicated in Fig. 1, so that as the holders 23 and 29 are forced toward each other by the spring 30 after the sections of the cloth beam have been placed in position, such inclined edges of the section expanders 125 will cause a separation of the edges of the sections engaged by said expanders and the opposite edges 37, 38 of said sections to approach each other and clamp the cloth 39 between them, Fig. 2. It will be noted from the described embodiment of the invention 130 that the cloth beam sections 25 and 26 are

not only separate and independent of each other, but when removed from cloth winding position in the loom that the said independent sections, by reason of the separation of the edges previously engaged by the section expanders, may be collapsed or moved toward each other sufficiently to disengage or unclamp the edges 37, 38 from the end of the cloth and to permit free removal 10 of the independent sections of the cloth beam from the cloth roll.

While the illustrated form of the present invention shows the cloth beam formed of two independent sections, it is apparent that 15 the number of sections may be varied to suit conditions of use and that particulars and details of the structure associated with the cloth beam may be varied within the true scope of the invention which is defined by the claims.

What is claimed is:

1. In a loom, the combination of a cloth beam comprising a plurality of independent longitudinal sections having cloth supporting surfaces, disconnected means acting on the ends of said sections for supporting them in operative position, a spring for yieldingly forcing one of said disconnected means toward the other and devices on said means 30 actuated by said spring for yieldingly forcing two adjacent edges of said sections toward each other for clamping an end portion of the cloth between them.

2. In a loom, the combination of a cloth beam comprising a plurality of independent longitudinal beam sections, section holders for engaging the ends of said independent sections, means for independently supporting said section holders, yielding means acting normally to force one of said section holders toward the other, and devices on said section holders rendered effective by said yielding means for causing adjacent edges of two of said beam sections to clamp an end portion of the cloth between them.

3. In a loom, a collapsible cloth beam, comprising independent longitudinal sections having cloth supporting surfaces, independently supported section holders on 50 the loom frame for engaging the ends of the sections, and means acting longitudinally of said sections for forcing said sections circumferentially of the cloth beam to clamp the end portion of the cloth between adjacent edges of said sections.

4. In combination, a cloth beam for looms comprising a plurality of independent longitudinal sections, independently supported holders for engaging the ends of said independent sections and maintaining them in cloth winding position, means on said holders for preventing collapse of said independent sections when in winding position, and means also on the independently supported section holders for causing adja-

cent edge portions of two of said sections to be clamped upon the cloth placed between them when the section holders are moved toward each other.

5. In a loom, the combination of independently supported beam section holders, independent beam sections adapted to be engaged by said holders and held in assembled relation, section expanders having inclined portions and carried by the holders 70 for holding the sections with two adjacent edges separated and other two adjacent edges in closed relation upon the end of the cloth to be wound, and means acting normally to force one section holder toward the other and the expanders in a direction to cause the beam sections to clamp the end of the cloth between them.

6. In a loom, the combination of a cloth beam comprising a plurality of independent beam sections, section holders for engaging the ends of said independent sections, means for independently supporting said section holders, yielding means acting normally to force one of said section holders toward the other to thereby hold the independent beam sections in operative relation to each other when in the loom and yielding to permit the disengagement of the beam sections from the holders and the collapse of said beam sections as they are removed from the loom.

7. In a loom, the combination of independent longitudinal beam sections, independently supported beam section holders for engaging the ends of said sections, automatic means for forcing one of said holders toward the other, means on said holders for preventing sections previously placed in position from being displaced while putting other sections into operative 105 position with respect to the holders.

8. In a loom, the combination of independent beam sections, beam section holders, means on the loom frame for independently supporting said holders, section expanders 110 having inclined edge portions to engage between beam sections for holding the sections with two adjacent edge portions separated and the other two adjacent edges clamped upon the cloth to be wound, and automatic means acting upon one of the section holders longitudinally of the beam sections to move them relatively in a direction toward each other and to cause the section expander to clamp the sections upon the cloth. 120

9. In a loom, the combination of independent longitudinal beam sections, section holders for engaging the ends of the beam sections, means for normally forcing one section holder toward the other, projections 125 on said beam holders to engage the end portions of the sections, a projection on one of the holders being of less extent than the other projections on the same holder to permit the beam sections to be placed in posi-

tion successively and prevent the previously positioned section from being displaced while putting the other section in position.

10. In a loom, the combination of a collapsible cloth beam comprising a plurality of independent longitudinal sections, section holders independently supported and adapted to engage the ends of the said longitudinal sections, inner and outer projections 5 on said holders to engage the inner and outer surfaces of said sections to hold them in cloth-receiving relation when in the loom, one of the outer projections on one of said

holders being constructed to permit the end of a section to be put in place after another 15 section without displacing said other section, and means for yieldingly forcing one of the section holders toward the other.

In testimony whereof, I have signed my name to this specification, in the presence of 20 two subscribing witnesses.

JONAS NORTHROP.
